UNITED STATES PATENT OFFICE.

JOHN E. GAITLEY, OF TROY, NEW YORK.

STOVE-GRIDDLE LIFTER.

SPECIFICATION forming part of Letters Patent No. 588,819, dated August 24, 1897.

Application filed March 28, 1896. Serial No. 585,206. (No model.)

To all whom it may concern:

Be it known that I, JOHN E. GAITLEY, of the city of Troy, county of Rensselaer, State of New York, have invented new and useful 5 Improvements in Stove-Griddle Lifters, of which the following is a specification.

My invention relates to improvements upon that class of devices which are termed "stove-lifters," and which are provided with a grasping-handle at one end, a foot at the other end adapted to engage with a recess formed in the griddle covering the pot-holes in the tops of stoves and ranges, and by which said griddles may be lifted or put in place; and the 15 object of my improvements upon this class of devices is to adapt them to be used in connection with griddles having differing-sized lifting-recesses.

Accompanying this specification, to form a 20 part of it, there is a sheet of drawings containing two figures illustrating my invention, with the same designation of parts by letter reference used in all of them.

Of the illustrations, Figure 1 is a perspective of my improved griddle-lifter shown as entered within a griddle-lifting recess and in a position to grasp the griddle so that it can be raised from out or returned to the pot-hole of a stove or range. Fig. 2 is a side elevation of my improved lifter shown as applied to lift a griddle, with the latter shown in diametrical section.

The several parts of the device thus illustrated are designated by letter reference, and 35 the function of the parts is described as follows.

The letter S designates the lifter-shank, which in this instance is shown as provided with an encircling coil handle made of wire, 40 which is arranged to encircle the shank between the shoulder h and the ring R on its outer end.

The letter L designates the leg of the lifter, which is provided with the foot F, having the 45 slot l. This foot at its toe end T is made to taper, so as to adapt it to enter differing-sized griddle-recesses.

The letter A designates a clutching-lever, which at each of its sides is provided with a 50 trunnion-journal J, these journals each being projected from one of the opposite sides of

the clutching-lever A, preferably back of its cross-center, and the letters a² designate arms, of which there is one at each end, arranged at right angles to the lever A.

55

The letters b² b² designate bearings formed in the heel end of the foot F, into which the journals J of the clutching-lever are entered and in which it is pivoted to oscillate.

The lifter, with the exception of the coil-wire handle, is preferably made of malleable cast-iron, into which the journal-bearings are cast with open ends, and into which the journals J are entered when the ends of the bearings are set inwardly to retain the journals in place.

The letters G designate a stove or range griddle, and D a lifting-recess formed therein, said recess having a lug d² projected inwardly from each of its opposite sides. As 70 thus made, when the toe end of the lifter is entered within the recess D, so as to pass beneath the lugs d², and the outer handle end is depressed the toe end will engage with the recess, and the clutching-lever A at both of 75 its ends will bear down upon the griddle-surface, so that the toe end will be held in place and the lifter will securely grasp the griddle. By thus making the toe end of the lifter-foot tapering it will, in combination with the 80 clutching-lever A, adapt the lifter to be used on griddles having differing-sized recesses, and one size of lifter will answer for a great variety of stoves and ranges.

I am aware that a lifter has been patented 85 in which a pivoted lever has been used, the outer end of which would engage with the griddle-top when the lifter was entered within a griddle-recess, but in this older device as constructed the inner end of the clutching-lever was pivoted to another lever, which at 90 its inner end was pivoted to the shank. In this older device the clutching-lever was pivoted to the top of the foot, and by pivoting it to the under side of the heel I am enabled 95 to dispense with the additional lever by which differing construction is made a necessary part of the older device alluded to, and to thus simplify and reduce the cost of construction.

Instead of the coil handle shown any well-known form of handle may be used.

Having thus described my invention, what

I claim, and desire to secure by Letters Patent, is—

In a lifter for stove or range griddles the combination with a handle provided with a shank and downcurved leg L having the laterally-extended foot F, provided with the slot l^2 , and bearings b^2 , b^3 , of the clutching-lever A, having the side journals J, J, and the arms a^2 , a^3 , constructed and arranged to

connect, and be operated substantially in the manner as and for the purposes set forth.

Signed at the city of Troy, this 13th day of November, 1895, in the presence of the two witnesses whose names are hereto written.

JOHN E. GAITLEY.
